TWIN ARC LAMP

Ernest G. Ashcraft, Los Angeles, Calif.

Application May 10, 1938, Serial No. 207,045

9 Claims. (Cl. 176—58)

This invention relates generally to arc lamps, and more particularly to arc lamps adapted especially for motion picture studio service, particularly for color photography, though not necessarily restricted to such service. A specific illustrative form of the invention relates to a type of studio arc lamp in which the carbons are disposed in vertical alignment, and is here illustratively described in a "twin arc" form, 5 in which two pairs of vertically aligned carbons are employed.

The vertical carbon twin-arc lamp as heretofore known in motion picture studio practice, employing an intermittent gravity feed principle for 15 advancing the upper carbons to compensate for consumption, is no longer considered appropriate for color picture service, since, owing to the intermittent feed, the intensity of the arc as well as its spectral distribution is subject to variation 20 of a character readily perceptible in the final picture.

In some types of twin arc lamps difficulty has been encountered due to the tendency of one pair of carbons to be consumed at a slightly 25 faster rate than the other. The differential in the rate of consumption is not great for modern well made carbons, but if no equalizing provisions are made, the difference in gap length of the two arcs may become appreciable before the 30 carbons are completely used.

It is accordingly a primary object of the invention to provide an arc lamp capable of maintaining the spectral distribution of its emitted light substantially constant under all conditions.

35 A further primary object of the invention is to provide improved carbon feeding means capable of automatically maintaining a predetermined distance of separation between the carbons of an arc lamp under all operating conditions.

40 It is a further object of the invention to provide an improved twin or multiple arc carbon feeding mechanism in which the arc gaps are equalized from time to time.

A further important object of the invention 45 is to provide an arc lamp of the character described with improved arc striking mechanism.

A further general object of the invention is to provide improved feeding and striking mechanism for an arc lamp of the type embodying 50 vertical carbons, capable of striking the arc by separating the carbons to a predetermined distance, and of maintaining said separation distance constant during operation of the lamp.

In accordance with the present invention, the 55 carbons are fed toward one another to compen-

sate for consumption by an electric drive motor, preferably a shunt motor, which is connected across the arc, and provisions are made whereby the voltage applied across the terminals of the motor for any line voltage within a substantial 5 working range, e. g., 105-120 volts, is proper to cause the motor to drive at the speed required to feed the carbons at the rate necessary to just compensate for consumption at that line voltage.

In accordance with a preferred embodiment 10 of the invention, the arc lamp mechanism is provided with upper and lower carbon carriages, which are gradually advanced toward one another by means of a lead screw driven by the electric drive motor. The upper carbon carriage 15 is adapted to loosely receive a carbon, or a pair or a multiplicity of carbons, for vertical movement therethrough, so that the upper carbons descend by gravity through the upper carriage and into engagement with the lower carbons 20 when the arc is extinguished. The lower carbons are preferably rigidly mounted on the lower carbon carriage. Means, preferably of a solenoid type, are mounted directly on the upper carbon carriage for gripping the upper carbons and 25 lifting them relatively to the upper carbon carriage to strike the arc when an electrical current is passed through the carbons. When the arc is extinguished, the two upper carbons descend by gravity into engagement with the lower carbons. 30 When the arc is again struck, the carbon lifting means on the upper carriage engages the two upper carbons and lifts them both exactly the same distance, to strike the arc and to position them at the proper distance of separation from 35 the lower carbons. The arc gap lengths are thus equalized each time the arc is extinguished and reignited. During burning of the arcs, the carbons are advanced toward one another at a speed which is substantially equal to their rate 40 of consumption, as mentioned previously, so that the desired arc gap lengths are closely maintained.

The invention will be best understood by now referring to the following detailed description 45 of illustrative means embodying the invention, reference being directed to the accompanying drawings, in which:

Fig. 1 is a front elevation of the mechanism; shown in inoperative position, with the carbons 50 touching;

Fig. 2 is a top plan view of the mechanism of Fig. 1;

Fig. 3 is a side elevation, parts being broken away, of the mechanism of Fig. 1;

- Fig. 3a is a detail section taken on line 3a—3a of Fig. 3;
- Fig. 4 is an enlarged view of a portion of Fig. 1, showing the mechanism in operating position;
- 5 Fig. 5 is a section taken as indicated by the broken line 5—5 of Fig. 3;
- Fig. 6 is a section taken on line 6—6 of Fig. 3;
- Fig. 7 shows the electrical circuit of the arc lamp; and
- 10 Figs. 8 and 9 are graphs illustrating relations provided in accordance with the invention.
- I will describe first one form of arc lamp mechanism illustrative of suitable means for carrying the present invention into practical effect.
- 15 Any suitable frame may be provided; as here illustratively shown, the frame includes upper and lower castings 10 and 11 connected by parallel vertical rods 12 and 13.
- 20 Tightly mounted on rods 12 and 13 are three mounting castings 14, 15 and 16, the first being positioned at the upper ends of rods 12 and 13 just below upper frame member 10, the second being positioned midway of the lengths of rods 25 12 and 13, and the third being positioned at the lower ends of said rods, just above lower frame member 11. Mounted on mountings 15 and 16 is the housing 17 for an electrical drive motor M, which is disposed with its drive shaft extending 30 in a vertical direction. This motor housing 17 is located just to the rear of the plane defined by rods 12 and 13, and just outside rod 12 (see Figs 1 and 3).
- Vertical motor drive-shaft 18 carries a worm 35 19, meshing with a worm wheel 20 on shaft 21, the latter having another worm 22 meshing with a worm wheel 23 tightly mounted on a vertically disposed lead screw 24. Below worm wheel 23, lead screw 24 is provided with a downwardly extending shaft portion 25 of reduced diameter, which is journaled, just below worm 23, in a bearing 26 carried by mounting 15.
- Bearing 26 has a shoulder at 27 resting on mounting 15, and its upper end supports lead 40 screw 24 by engaging the undersurface of worm wheel 23.
- Pinned on shaft 25 below mounting 15 is a coaxial lead screw 30. The upper end portion of lead screw 24 and the lower end portion of 45 lead screw 30 are suitably journaled in mountings 14 and 16, respectively. The upper carbon holder or carriage, designated generally by numeral 40, embodies a frame member 40a having hub portions 41 and 42 slidably mounted on 50 parallel rods 12 and 13. Adjacent hub portion 42 frame 40a has a bore 43 within which is received the upper end of a shaft 44 extending downwardly in parallelism with rods 12 and 13, shaft 44 being rigidly secured to frame 40a as 55 by pin 45. This shaft 44 is telescopically received by a tube 46 mounted at its lower end in mounting 16 and extending upwardly through a bore 47 in mounting 15, the upper end of tube 46 terminating just above the latter.
- 60 A lower carbon holder or carriage 50 similarly comprises a frame 50a provided with hub portions 51 and 52 slidably receiving rods 12 and 13, and having, adjacent hub portion 51, a bore 53 receiving the lower end of a shaft 54 extending 65 upwardly in parallelism with rods 12 and 13, shaft 54 being rigidly secured to carriage 50 as by means of pin 55. Carriage frame 50a is provided with a bore 56 which slidably passes the aforementioned fixed sleeve 46. Upwardly extending shaft 54 is slidably received by a sleeve 70 75

57 rigidly mounted at its upper end on mounting member 14 and extending downwardly therefrom through a bore 58 in mounting 15, the sleeve terminating just below mounting 15 as clearly indicated in Fig. 4. Upper carbon carriage frame 5 40a is provided with a bore 59 which slidably receives sleeve 57.

The upper and lower carbon carriages are thus mounted for vertical movement along the described guide members. Releasable connections are provided between said carriages and lead screws 24 and 30, which are of opposite pitch, so that when said lead screws are rotated, the carbon carriages will be moved toward one another, and so that the connections between 10 the carbon carriages and the lead screws may be released for quick adjustment of the carriages along the lead screws.

Thus the upper carbon carriage has a pair of vertically spaced rearwardly extending plates or 20 brackets 65, between which are pivotally mounted a pair of levers 66. As shown in the drawings, each lever 66 has a hub 67 pivotally mounted on a pin 68 extending between brackets 65. The forwardly extending arms 70 of 25 levers 66 are provided with nut elements 71 adapted to threadably engage opposite sides of lead screw 24. A spring 74 between the rearward arms 75 of levers 66 spreads arms 75 to hold nut elements 71 in yielding engagement with 30 lead screw 24. The rearward ends of arms 75 are provided with finger pieces 76 by which arms 75 may be conveniently grasped to move them together for the purpose of releasing threaded 35 elements 71, and therefore upper carbon carriage 40, from the lead screw.

Lower carbon carriage 50 is provided with rearwardly extending brackets 80, between which are pivotally mounted manually releasable lead screw engaging levers 66 which may be exactly 40 similar to the levers 66 on the upper carbon carriage, levers 66 on the lower carriage having nut elements 71 adapted to releasably engage lower lead screw member 30, as clearly indicated in the drawings.

Lower carbon carriage 50 has two arms 90, to the outer ends of which are secured carbon holders 91, which may be of any suitable type adapted to receive and clamp the lower ends of a pair of vertical carbons 92. As here shown, holders 91 50 contain split bushings 91a adapted to clamp carbons 92 when screws 91b are tightened. Carbon holders 91 are provided with threaded studs 94 which extend through arms 90, nuts 95 being screwthreaded on said studs to secure the carbon holders in assembly with the arms of the carriage. Electrical connectors 96 clamped between nuts 95 serve to conduct electrical current to the carbon holders. The carbon holders and studs 94 are insulated from arms 90 by suitable 60 insulation such as indicated at 97.

Upper carbon carriage 40 has a forwardly extending bracket 100, to which is secured a pair of diverging arms 101 and 102, each of which has, at its outer end, a pair of horizontal, vertically 65 spaced brackets 103 and 104. The inner ends of arms 101 and 102 are perforated to receive screws 106 and surrounding insulation sleeves 107, screws 106 being screwthreaded into bracket 100, as clearly illustrated in Fig. 5. Insulation washers 108 insulate arms 101 and 102 from bracket 100.

Brackets 103 and 104 at the outer end of each of arms 101 and 102 are provided, in alinement with lower carbons 92, with perforations 105 75

adapted to slidably receive vertical upper carbons 110. Electrical connectors 110a are clamped directly on the upper ends of carbons 110. Carbons 110 descend by gravity through brackets 103 and 104 into engagement with the upper ends of carbons 92 when the arc is extinguished, and are engaged and lifted with relation to the upper carbon carriage to strike the arc by means supported by and travelling 5 with the carriage itself. While various means may be provided to accomplish this purpose, I here illustrate a simple mechanism comprising carbon engaging clutches in the form of flat plates 120, one for each carbon, each having a 10 carbon receiving perforation 121 midway between its ends which is somewhat larger in diameter than the diameter of the carbon, and being positioned between the aforementioned brackets 103 and 104, as illustrated. Clutch plates 120 15 normally, that is, when the arc is not burning, rest down on lower brackets 104, as illustrated in Fig. 1. Each plate 120 has at one end a perforation 122 somewhat loosely receiving a screw 123 which also passes downwardly through bracket 20 104. A nut 124 on the lower end of screw 123, below bracket 104, is so positioned as to permit plate 120 to be lifted to the position illustrated in Fig. 4, at which point the head of the screw acts as a stop preventing further upward movement 25 of the plate.

Plates 120 are adapted to be lifted by means of links 130 connected to their other ends, the latter being looped at their upper ends around insulation sleeves 132 mounted on a horizontal rod 35 134. Rod 134 passes through a central mounting 135, which is secured on and carried by the outer swinging end of a lever member 136. Collars 136a set on rod 134 on opposite sides of mounting 135 confine the rod against endwise displacement.

As here illustratively shown, lever 136 is in the form of a rod which is bent double, its two ends being received in openings 137 in mounting 135, and being secured thereto by screws 138. The two arm portions 136a of the rod extending rearwardly from mounting 135 are bent upwardly at 139, so as to pass through loops 140 formed in the ends of clips 141 pivotally mounted at 141a on arms 100 (see Fig. 5), and are then bent rearwardly, as at 142, to form portions 143 passing around opposite sides of lead screw 24. The loop end of the rod, rearwardly of lead screw 24, engages in a notch 150 formed in the upper end of the vertically movable plunger 151 of a solenoid 152. A pin 153 closes notch 150 above the loop end of lever 136, so that when solenoid 152 is energized and pulls plunger 151 in a downward direction, pin 153 will engage and pull down the loop end of lever 136. Lever 136 is thus furcured by pivotally mounted clips 141. A spring 165 connected between mounting 135 and carriage frame 40 returns lever 136 and solenoid plunger 151 to the position of Figs. 1 and 3 when the solenoid is deenergized.

Solenoid plunger 151 is slidable through a sleeve 160 extending through and tightly fitted in bracket arms 65 between levers 66 (Fig. 5), the solenoid being secured to the lower end of said sleeve, so that it is mounted directly on or is carried by the vertically travelling upper carbon carriage. Thus, as illustratively shown in Fig. 3, the lower portion of sleeve 160 is reduced, as at 161, and the case of solenoid 152 is mounted thereon as by means of a press fit.

Fig. 7 shows the electrical circuit for the arc

lamp. The upper member of one pair of carbons is connected by circuit conductor 170 to one terminal of the winding of solenoid 152, the other terminal of which is connected through a usual voltage reducing resistance or grid 171 and through line switch 190 to the positive side of the line, as indicated. The lower carbon 92 of the other pair is connected by lead 172 through switch 190 to the negative side of the line. The upper carbon of the latter pair and the lower 10 carbon of the former are connected by a conductor 170a, so that the two pairs of carbons are series connected across the line. The shunt drive motor M for lead screws 24 and 30 is connected by leads 174 and 175 across the positive and 15 negative leads 170 and 172 going to the carbons, one of said leads, here lead 175, including a resistor 175a, which may be variable, and is so indicated in Fig. 7. The shunt field winding f of motor M is preferably connected across resistor 175a as well as the armature of the motor, as indicated. With this arrangement, the speed 20 of the motor is more sensitive to the adjustment of resistor 175a. I have stated that lead 170 goes to the positive side of the line and lead 172 25 goes to the negative side of the line; it is to be understood, however, that this is not necessary, and that the lamp will operate with the reverse polarity as well. Resistor 171, ordinarily called the grid, is used since the usual available D. C. voltage 30 is excessive for the carbons used in this type of lamp.

The voltage across the motor armature during running conditions is the voltage across the two series connected arcs, less the IR drop in resistor 35 175a. Motor M runs at a speed proportional to this impressed voltage, driving the two carbon carriages toward one another to compensate for consumption of the carbons.

When the arc is extinguished, the mechanism 40 stands in the position of Figs. 1 and 3, with solenoid 152 deenergized, and lever 136 held by spring 165 with its forward arm portions 136a in downward position. Clutch plates 120 are therefore resting on brackets 104, and upper carbons 110 45 are free to slide by gravity through brackets 103 and 104 until their lower ends engage the upper ends of lower carbons 92.

When line switch 190 is closed, electrical current flows through circuit 170, 172 and through 50 the carbons, then touching. Solenoid 152 is accordingly energized, and pulls plunger 151 down. This swings lever 136 to elevate rod 134, which lifts links 130 to pull clutch plates to their upper, tilted position of Fig. 4. As the clutch 55 plates are first tilted in this action, they bind carbons 110, and as they are then elevated to the position of Fig. 4, they lift the carbons, thereby striking the arc. The distance the carbons are lifted depends of course upon the adjustment of 60 stop screws 123, which are so adjusted that the carbons will be lifted a distance exactly equal to the separation distance between the tips of the carbons for proper operation. This separation distance is typically $\frac{1}{16}$ ".

The arc being struck, a potential difference is established thereacross, and shunt motor M begins to run. When the arc is subsequently extinguished, as by opening switch 190, solenoid 151 is deenergized, and lever 136 is accordingly 70 released and moves to allow clutch plates 120 to descend to brackets 104. Upper carbons 110 are accordingly released by the upper carriage, and descend by gravity until their lower ends engage the upper ends of lower carbons 92. When line 75

switch 190 is then again closed, solenoid 151 is again energized and causes the carbons to be lifted to strike the arc, the carbons again being moved at once to their proper equal separation 5 distance.

Thus it is characteristic of the invention that the upper carbons are loosely held by the upper carriage when the arc is extinguished, and that when the arc is struck, means on the upper carriage engage the upper carbons and lift them by a distance equal to their normal distance of separation from the lower carbons. The shunt drive motor driving the upper and lower carriages then closely maintains this separation distance during burning of the arcs, as will be more fully discussed infra.

It is an important feature of my invention that the separation distances between the carbons are equalized each time the arc is extinguished 20 and re-struck, since the carbon holding clutch plates then take a new hold on the upper carbons and lift them both to exactly the same separation distance from the lower carbons. In motion picture studio service the lamp of course does 25 not normally burn for periods longer than say about ten minutes at a time, and in such a short period of time no appreciable difference in the distances of separation of the carbons, i. e., none of which will have any noticeable effect on the 30 quality of the light, will occur. And since the separation distances of the carbons are automatically equalized each time the arc is extinguished and re-struck, there is never any greater than a negligible differential between the lengths 35 of the two gaps, and any such differential as may exist will be so slight that it may be disregarded.

When new carbons are to be placed in the lamp, levers 66 are operated to release the carbon carriages from the lead screws, and the carriages may then be readily and quickly moved to the 40 outer ends of the guide rods. New carbons are then inserted, after which the lower carbon carriage is adjusted to bring the upper ends of the lower carbons to the proper working height. The lamp is then in readiness for operation.

Reference is now directed to Figs. 8 and 9. Fig. 8 is a graph in which curve 200 represents the relation between the impressed line voltage and the average of the rates of consumption, in 50 inches per hour, of the positive and negative carbons of one arc. It is of course understood that, assuming equal diameter positive and negative carbons, the positive carbon is consumed slightly faster than the negative carbon. Curve 200 does not express the exact rate of consumption 55 of either the positive or the negative carbon, but the average of the individual rates of consumption of the two. The line voltage may be assumed to vary from 105 to 120 volts. This voltage is reduced somewhat by the drop across resistor 171, while the impressed voltage across each arc is of course half of the voltage measured across the two pairs of carbons. Thus for a line voltage of 115 volts, there may be an average 60 potential of 33 volts across each arc. The curve of Fig. 8 thus represents the relation between the impressed line voltage and the average of the rates of consumption of the two carbons.

Fig. 9 shows two curves representing the relations for two different lamp mechanisms between the impressed line voltage and the speed, in 65 inches per hour, at which each one of the carbons is advanced. It will be understood that the speed of advance of one of the carbons may be calculated by dividing the motor speed by the drive 70

ratio between the motor and the speed of travel of the corresponding carriage or holder for the carbon.

In the present embodiment of the invention, 5 the speeds of the two carbon carriages are made equal, though it is obvious they may if desired be made sufficiently different so as just to compensate for the difference in rates of consumption of the positive and negative carbons. It will be evident that with the speeds of advance 10 of the two carbons exactly equal to one another, and also maintained equal to the average of the rates of consumption of the positive and negative carbons, the position of the arc gap will gradually drift in the direction of the positive 15 carbon, at a speed equal to the differential of the speed of consumption of the positive and negative carbons. This drift is comparatively slight, however, and introduces no difficulty.

Curve 201 represents a lamp mechanism in 20 which, for one given line voltage only, the rate of carbon feed is just equal to the average of the rates of carbon consumption for that given line voltage, as read from the graph of Fig. 8. Thus, for voltage A, the rate of carbon feed is 25 just equal to the average of the rates of carbon consumption, and if the graph of Figs. 8 and 9 were superimposed, curves 200 and 201 would coincide at one point a. At other impressed line voltages, however, there is no point of substantial 30 coincidence on both curves 200 and 201, and the carbons will therefor no longer be fed at rates equal to their average rate of consumption, with the result that the arc gap will either widen or close.

Curve 202 of Fig. 9 represents the condition established in accordance with the present invention. By proper adjustment of the voltage impressed across the drive motor, and proper choice of the drive ratio between the motor and the carbons, curve 202 is matched to curve 200 of Fig. 8, and if Figs. 8 and 9 were superimposed, curves 200 and 202 would approximately coincide for at least the range of impressed line voltages for which the mechanism is designed, e. g., for a 40 range of line voltages ranging from 105-120 v. It will be evident from a comparison of curves 200 and 202 that for any line voltage within the range from B to C, the rate of carbon feed will exactly or substantially equal the average of the 45 rates of carbon consumption. Accordingly, assuming the carbons to have initially been separated to a proper distance, that distance will be maintained regardless of variations in line voltage, the speed of the motor varying with 50 changes in line voltage, but varying always so as to keep the rate of carbon feed equal to the average of the rates of carbon consumption. The distance of carbon separation, and therefore the 55 spectral distribution of the emitted light, accordingly remains constant for any change in line voltage at least as great as from 105 to 120 volts.

The method of and means by which the carbon feed characteristic for changing impressed voltage is matched to the carbon consumption characteristic for changing impressed voltage, as accomplished by the present invention, will now be described. The impressed line voltage-carbon 65 consumption characteristic curve is of course 70 governed by the consumption characteristics of the carbons to be used. The impressed line voltage-carbon feed characteristic depends upon several factors, among which are the magnitude of the voltage actually impressed across the 75

terminals of the motor, and the drive ratio between the motor and the carbon advancing means. Accordingly, in the present simple illustrative embodiment of the invention, resistor 175a is used in series with the armature of motor M, and preferably "inside" of field winding f, and this resistor is adjusted to establish the motor speed characteristic at such a value as will give the characteristic sought for a properly chosen drive ratio. It is believed the invention may best be illustrated by here giving data on one typical practical embodiment of the invention, though it is to be understood, of course, that these figures are illustrative only of one practical work-out of the invention and are not to be taken in a limitative sense. With this understanding, it may be assumed that the lamp is to use cord, copper coated carbons, $\frac{5}{16}$ " in diameter, of the type produced by National Carbon Co., and known as Motion Picture Studio carbons. Resistance 171, usually known as the grid, may be of a resistance of about 1.1 ohms, so that for a line voltage of 115 v., the voltage across the series connected carbons will be approximately 66 v., or 33 v. across each arc. Resistor 175a is then adjusted to a resistance of substantially 100 ohms. This resistance may require somewhat fine adjustment to establish the precise characteristic sought. Motor M may typically be an ordinary 115 v. direct current shunt motor, rated at .5 a. and $\frac{1}{40}$ H. P. The proper drive ratio between the shaft of motor M and each of the carbons is then 1728 to 1.

A lamp mechanism having these characteristics maintains the lengths of its two arc gaps very closely for variations in line voltage between 105 and 120 v. Some slight change in gap length is detectable but not sufficient to vary the spectral distribution of the emitted light by a degree which is at all undesirable from the standpoint of motion picture color photography. Of course, under present studio conditions, a line voltage variation of no greater than approximately four or five volts is ordinarily encountered, and in present practice, therefore, it will ordinarily be amply sufficient if the lamp maintains a substantially constant gap for a range of line voltages as great as say four or five volts. The degree of voltage variation necessary to be provided for will thus depend in given cases upon conditions as they are encountered in studio service. The specific lamp as herein disclosed is capable of maintaining a substantially constant gap for a wider range of line voltages than is ordinarily met with, namely, for a range as great as fifteen volts. Such a condition is advantageous, however, even when the line voltage varies with a range of a very few volts, since with a lamp designed to maintain the gap width substantially constant for a greater range of voltages than will actually ordinarily be encountered, there is assurance that the gap will be very steady with lesser voltage variations than do occur with relative regularity.

The instantaneous voltage across one arc, if examined carefully, may be found to vary as much as plus or minus two volts in a somewhat irregular way due to air currents and non-uniformity of core materials of the carbons. Voltage variations from this cause are transitory in character, however, and do not appreciably affect motor speed because of the momentum of the motor and parts driven thereby. Moreover, the plus and minus voltage variations when averaged over a short period of time will nearly cancel and

for practical purposes may be neglected. The variations in voltage introduced by changing line voltage, on the other hand, are essentially more gradual, and are the variations with which the present invention is concerned.

It is of course true that the intensity of the emitted light is substantially lower at a line voltage of 105 v. than at a line voltage of 120 v. This condition is not at all serious, however, since it may readily be compensated by use of more or less lamps. What the present lamp does accomplish, which so far as my knowledge goes, is entirely novel, is to maintain the spectral distribution or color value of the emitted light substantially constant under all conditions encountered in studio service, an accomplishment of utmost importance to color motion picture photography.

I have now illustrated my invention embodied in a twin arc type of lamp employing vertically aligned carbons, in which both carbons are fed, and are fed at the same speed. It is of course obvious that my invention is also applicable to other types of arc lamps, and is applicable whether both carbons of each arc are fed at the same or different speeds, or only one carbon of each arc is fed. If but one carbon of each pair is fed, for example, it will simply be fed at twice the speed as in the case of both carbons being fed at equal speeds. The fundamental basis of the invention, namely, matching of the impressed voltage-carbon feed characteristic to the impressed voltage-carbon consumption characteristic, for the range of line voltage encountered in practice, rather than for a single line voltage, is thus applicable to all such situations. An arc lamp mechanism in accordance with the present invention is stable in operation and maintains the predetermined length of its arc gap for all conditions encountered in the field. No hand feed for readjustment from time to time of the arc gap is required, and no operator need stand in constant attendance. The lamp requires only that the arcs be struck, which is done automatically when the line switch is closed, and then automatically maintains its arc gaps with all the necessary constancy and accuracy called for by present color motion picture photography practice without further attention.

I have now shown and described one present illustrative embodiment of the invention; it will of course be understood that this is for illustrative purposes only and that the present invention is applicable to other types of arc lamps as well. It should also be understood that while I have referred to my invention chiefly in connection with color motion picture photography, its full field of application is much wider than this, as it is also applicable to projection of color motion pictures, or to studio or projector use with black and white film, or to any other service calling for a stable arc lamp.

I claim:

1. In an arc lamp the combination of a frame, upper and lower carbon carriages mounted for vertical movement on said frame, drive means on said frame operatively connected with both said carbon carriages for continuously and uninterruptedly advancing said carriages toward one another, a carbon holder on said lower carbon carriage for tightly gripping a lower carbon, an upper carbon guide on said upper carbon carriage having a carbon guideway adapted for free passage of the upper carbon and located in alignment with the lower carbon gripped by the carbon holder on said lower carriage, and a carbon

clutch and operating means therefor associated with said upper carriage for gripping said upper carbon and elevating it a predetermined distance through said carbon guide.

5. 2. In an arc lamp, the combination of a frame, upper and lower carbon carriages mounted for vertical movement on said frame, drive means on said frame operatively connected with both said carbon carriages for continuously and uninterruptedly advancing said carriages toward one another, a carbon holder on said lower carbon carriage for tightly gripping a lower carbon, an upper carbon guide on said upper carbon carriage having a carbon guideway adapted for free 10 passage of the upper carbon and located in alinement with the lower carbon gripped by the carbon holder on said lower carriage, and a carbon clutch and operating means therefor mounted on and travelling with said upper carriage for gripping 15 said upper carbon and elevating it a predetermined distance through said carbon guide.

3. In an arc lamp the combination of a frame, upper and lower carbon carriages mounted for vertical movement on said frame, drive means 25 on said frame operatively connected with both said carbon carriages for continuously and uninterruptedly advancing said carriages toward one another, a carbon holder on said lower carbon carriage for tightly gripping a lower carbon, an upper carbon guide on said upper carbon carriage having a carbon guideway adapted for free 30 passage of the upper carbon and located in alinement with the lower carbon gripped by the carbon holder on the said lower carriage, a carbon clutch on said upper carriage operable to grip and elevate said upper carbon a predetermined distance through said carbon guide, and electromagnetic clutch operating means mounted on said upper carriage and operatively connected with said clutch in a manner to cause 35 said clutch to grip and elevate said carbon when electrically energized and to hold said clutch in carbon elevated position until deenergized.

4. In an arc lamp, the combination of a frame, upper and lower carbon carriages mounted for vertical movement on said frame, drive means 45 on said frame operatively connected with both said carbon carriages for continuously and uninterruptedly advancing said carriages toward one another, a carbon holder on said lower carbon carriage for tightly gripping a lower carbon, an upper carbon guide on said upper carbon carriage having a carbon guideway adapted for free 50 passage of the upper carbon and located in alinement with the lower carbon gripped by the carbon holder on the said lower carriage, a carbon clutch on said upper carriage operable to grip and elevate said upper carbon a predetermined distance through said carbon guide, electromagnetic 55 clutch operating means mounted on said upper carriage and operatively connected with said clutch in a manner to cause said clutch to grip and elevate said carbon when electrically energized and to hold said clutch in carbon elevated position until deenergized, and an electrical energizing circuit connecting said carbons and said electromagnetic means in series.

5. In an arc lamp, the combination of upper and lower carbon supporting devices, means on 70 said lower carbon supporting device for gripping a lower carbon, an upper carbon guide having a carbon guideway adapted for free passage of the upper carbon and located in alinement with the lower carbon gripped by the lower carbon supporting device, drive means for effecting con-

tinuous uninterrupted relative movement of said carbon supporting devices toward one another along a direction line parallel to said carbons, a normally released carbon gripping and lifting clutch associated with the upper carbon-supporting device operable to grip and then elevate the lowered upper carbon a predetermined distance relative to the upper carbon-supporting device, a clutch-operating electromagnet mounted on the upper carbon supporting device and arranged 10 for operation of said clutch to grip and so elevate said carbon when energized and to sustain said carbon in such relatively elevated position until deenergized, and electrical connections through which said electromagnet is energized 15 whenever electrical current passes through said carbons.

6. In an arc lamp, the combination of upper and lower carbon supporting devices, means on 20 said lower carbon supporting device for gripping a lower carbon, an upper carbon guide on said upper carbon supporting device having a carbon guideway in alinement with said lower carbon supporting device, drive means for effecting continuous uninterrupted relative movement 25 of said carbon supporting devices toward one another, an electromagnet mounted on said upper carbon supporting device, a carbon gripping and lifting member associated with the upper carbon-supporting device comprising a clutch plate 30 surrounding said upper carbon and limitedly movable with relation to said carbon supporting device between a lowered substantially horizontal position and an upper tilted position, said plate releasably passing said carbon when in said 35 lowered, substantially horizontal position, and gripping and then elevating said carbon when tilted and then elevated to said upper, tilted position, means, including an operative connection with one end of said clutch plate, operated 40 by said electromagnet to so tilt and elevate said clutch plate, and to sustain said clutch plate in said tilted and elevated position until deenergized, and electrical connections through which 45 said electromagnet is energized.

7. In an arc lamp, the combination of upper and lower carbon supporting devices, means on 50 said lower carbon supporting device for gripping and supporting a plurality of lower carbons in parallel positions, a corresponding plurality of upper carbon guides on said upper carbon supporting device having carbon guideways in alinement with the respective lower carbons, drive means for effecting continuous uninterrupted relative movement of said carbon supporting devices toward one another along a line of travel 55 parallel to said carbons, and arc striking means supported by the upper carbon-supporting device including a plurality of carbon gripping and lifting devices normally released from the upper carbons, electromagnetic means operating said devices to grip and elevate said carbons a predetermined distance when energized with an electric current and to sustain said carbons in such relatively elevated position until deenergized, and an electrical energizing circuit connecting pairs of corresponding upper and lower carbons and 60 said electromagnetic means in series.

8. In an arc lamp, the combination of a frame, upper and lower carbon carriages mounted for 70 vertical movement on said frame, drive motor means on said frame operatively connected with both said carbon carriages for continuously and uniformly advancing said carriages toward one another, a carbon holder on said lower carbon 75

carriage for tightly gripping a lower carbon, and an upper carbon clutch on said upper carriage for gripping the upper carbon when the latter is in end to end engagement with the lower carbon and elevating it a predetermined distance relative to the upper carbon carriage.

9. In an arc lamp, the combination of a frame, upper and lower carbon carriages mounted for vertical movement on said frame, drive motor means on said frame operatively connected with both said carbon carriages for continuously and uniformly advancing said carriages toward one another, a carbon holder on said lower carbon

carriage for tightly gripping a lower carbon, an upper carbon clutch on said upper carriage for gripping the upper carbon when the latter is in end to end engagement with the lower carbon and elevating it a predetermined distance relative to the upper carbon carriage, and electromagnetic clutch operating means for causing said clutch to grip and elevate said upper carbon, said electromagnetic means being mounted on and travelling with said upper vertically travelling carriage.

ERNEST G. ASHCRAFT.
